BED DAVENPORT

Filed Oct. 27, 1924

2 Sheets-Sheet 1

This technical drawing illustrates a sofa's internal structure and exterior. The sofa is shown in an open, U-shaped configuration. The exterior is defined by a backrest (10) and a base frame. The base frame features curved, scroll-like legs (16) at the corners. A central support structure (11) is visible. The interior is divided into three sections, each supported by a curved spring (12) and a rectangular base (13). The backrest (10) is supported by a horizontal beam (14). Various components are labeled with numbers: 1, 2, 3, 4, 5, 6, 7, 8, 9, 10, 11, 12, 13, 14, 15, 16, 17, 18, 19, 20, 21, 22, and 23. Reference lines labeled I, II, and III indicate specific points of interest along the sofa's profile.

A technical line drawing of a chair. The backrest is labeled 4 and the seat is labeled 10. The seat features a wavy pattern. The legs are labeled 16 and the base is labeled 1. A vertical support on the left is labeled 3. A horizontal bar is labeled 5. The drawing includes a scale bar labeled 'T 10 C' and a reference line labeled 'Ed'.

Asst Clerk

ATTORNEY

UNITED STATES PATENT OFFICE.

EDWARD P. FARRELL, OF TOLEDO, OHIO.

BED DAVENPORT.

Application filed October 27, 1924. Serial No. 746,082.

To all whom it may concern:

Be it known that I, EDWARD P. FARRELL, a citizen of the United States of America, residing at Toledo, Lucas County, Ohio, have 5 invented new and useful Bed Davenports, of which the following is a specification.

This invention relates to extensible furniture.

This invention has utility when adapted 10 to a davenport for conversion thereof into a bed.

Referring to the drawings:

Fig. 1 is a front elevation, with parts broken away, of an embodiment of the invention in a davenport in collapsed or davenport assembly;

Fig. 2 is a section on the line II—II, Fig 1;

Fig. 3 is a plan view of the davenport of 20 Fig. 1 with the auxiliary frame or extension outward;

Fig. 4 is a section on the line IV—IV, Fig. 3, and

Fig. 5 is an end elevation from the left of 25 Fig. 3, on a reduced scale.

The article of furniture is shown as comprising a main frame having rear side 1 and front side 2. From the rear side 1 rises back 3 carrying upholstering 4. Between the 30 front and rear sides 1, 2, at the termini of the back 3 extend arms or ends 5, 6. Webbing or supporting means 7 carried by the main frame sustains rows of coil springs 8. These rows of springs 8 are housed by padded jacket or covering 9 to form a main upholstering or covered spring structure. On 35 this main upholstering portion may be removably disposed minor upholstering portions or pillows 10 as the normally over-stuffed structure of the davenport.

Between the rear side 1 and the front side 2 extend parallel rods or wires 11 which are held taut and disposed in the midst of the main upholstering section independently of 45 the operation or support of said springs or this main upholstering section. Disposed above each of these wires 11 is an element or slat 12 of an auxiliary frame. Each of these slats 12 carries an eye 13 embracing a wire 50 11 below such slat 12 and serves as a guide for the slat 12. These slats 12 extend through openings 14 in the front 2 and there engage auxiliary frame front member 15. This auxiliary frame front member 15 serves as a 55 false front for the davenport front side 2, and when it is desired to use this davenport

as a bed or extension structure, it is only necessary to draw this false front 15 away from the front side 2 of the davenport. In this operation the slats 12 slide in a plane 60 substantially midway between the plane of the upper and lower coils of the springs 9 and through the openings 14 and are guided by the eyes 13 as sliding on the rods 11. These eyes 13 in fully distended position of 65 the structure abut the front side 2. Legs 16 normally support the davenport main frame.

The auxiliary frame 15, 12, has in certain of the slats 12, openings 17. Hinge pins 18 mount legs 19 for swinging out of such opening 17 into supporting position for the davenport extension. As this davenport extension is thus withdrawn and supported, pillows 10 as the minor upholstery sections or portions may be disposed on the slats 12 to 70 bring the level of these cushions or pillows 10 to approximate the plane of the upper side of the main upholstery portion. The structure is thus of a uniform bed level and extent for receiving such sheets, blankets, or 75 covers as may be desired in the making up of the bed for sleepers or invalids.

Where the arm 6 is shown as having sections 20 as movable therefrom with the auxiliary frame section 15, this uprising portion 80 is a sort of head for the bed has rods 21, 22, extending therefrom through openings 23 in the arm 6. In the fully withdrawn position of the auxiliary frame, heads 24 on these rods 21, 22, abut the outer wall of the arm 90 6 to limit the outward movement of this portion of the auxiliary frame.

When it is desired to re-convert this bed into this davenport structure, it is only necessary to remove the loose bedding, shift 95 the pillows 10 off the extension frame to position over the main upholstery portion or section, snap the legs 19 back into the seats 17, and thrust the auxiliary frame into collapsed position with the davenport main 100 frame.

In this structure, the davenport has its full utility as an over-stuffed article of upholstered furniture without anything to detract from its appearance as a complete 105 davenport. The conversion is simply effected and provides a distribution of the upholstery for spring or mattress or spring and mattress utility in the bed structure.

What is claimed and it is desired to secure by Letters Patent is:—

1. A convertible bed upholstery struc-

- ture comprising rows of coil springs, a main frame provided with means supporting said springs, a covering for said springs, and an auxiliary slidable frame having intermediate slats coacting with the main frame to telescope into said covered spring structure substantially midway between the planes of the upper and lower coils of said springs independently of modifying the upholstery 5
- 10 operation of said covered spring structure, whereby the said slidable frame may be extended to receive a cushion of substantially the same thickness as the portion of said covered spring structure above the said 15 slats.
2. A convertible bed upholstery structure comprising a main frame, rows of coil springs, supporting means for said springs, said means being carried by said frame to 20 sustain the springs as to the frame for an upholstery structure, and an auxiliary frame having parallel intermediate elements mov-

able in for collapsing into and out for extending from said main frame, said elements being positioned substantially midway between the planes of the upper and lower coils of said springs. 25

3. A convertible bed upholstery structure comprising a main frame, a support therefor, rows of coil springs associated 30 with said frame, a housing for said springs assembled to provide a complete upholstery structure, an auxiliary slidable frame having intermediate slats positioned between said rows of springs and intermediate the lower portion of said first mentioned frame and the top of said housing with clearance downward from the housing for the springs permitting spring coaction in said complete upholstery structure independently of modification by said auxiliary slidable frame. 35 40

In witness whereof I affix my signature.

EDWARD P. FARRELL.
